UNITED STATES PATENT OFFICE.

PHINEAS B. MYERS, OF MORRISTOWN, NEW JERSEY.

DESIGN FOR A PAPER BOX.

No. 37,862.

Specification for Design.

Patented Feb. 27, 1906.

Application filed January 25, 1906. Serial No. 297,910. Term of patent 7 years.

To all whom it may concern:

Be it known that I, PHINEAS B. MYERS, a citizen of the United States, residing at Morristown, Morris county, State of New Jersey, have invented a new, original, and ornamental Design for Paper Boxes, of which the following is a specification, reference being had to the accompanying drawing, forming part thereof.

The figure is a perspective view of a paper box, showing my new design.

What I claim is—

The ornamental design for a paper box, as shown.

PHINEAS B. MYERS.
